ALGERNON C. EGGERT, OF COLUMBUS, OHIO.

PROPORTIONING-DRUM FOR MIXING FERTILIZER MATERIALS.

1,198,900.

Specification of Letters Patent. Patented Sept. 19, 1916.

Application filed February 17, 1915. Serial No. 8,921.

To all whom it may concern:

Be it known that I, ALGERNON C. EGGERT, citizen of the United States, residing at Columbus, in the county of Franklin and State 5 of Ohio, have invented a certain new and useful Improvement in Proportioning Drums for Mixing Fertilizer Materials, of which the following is a specification.

Soils in different regions differ very 10 greatly in their chemical composition, and fertilizer is oftentimes applied wastefully and without a knowledge as to what is best for the particular crop to be raised. Fertilizer has heretofore been usually furnished 15 ready-prepared and oftentimes ill adapted to the requirements of the particular soil to which it is applied. The more advanced and profitable method is to select a mixture adapted to the particular soil. It is rapidly 20 becoming clear to the farmer that it is economy to purchase only those materials which his particular soil requires, and the object of this invention is to provide a simple, inexpensive and convenient means whereby 25 those materials, if there be a number of them, can be automatically mixed in regulated proportions.

The invention is embodied in the example 30 herein shown and described and then particularly claimed.

Figure 1 is a view in front elevation with parts broken out and in section. Fig. 2 is a 35 combined top plan view and horizontal section of the proportioning drum. Fig. 3 is a vertical section on the line 3—3 Fig. 1, a portion only of the hopper being shown.

The proportioning device includes a drum 5 of cylindrical form of sheet metal that is divided vertically by wooden partitions 6 40 set transversely between longitudinal wooden walls 8 to form large end cells 9 and by longitudinal walls 10 and a transverse wall 11 to form intermediate smaller cells 12. Each cell is provided with a stationary 45 wooden bottom as at 13. The larger cells serve to measure the materials the proportions of which are greater than others in a given mixture. To control the proportions of materials measured with great nicety I 50 provide each cell with a movable upwardly curved bottom 22 of sheet metal provided with a central threaded nut 14. The curve of the upper side of the bottom 22 conforms 55 to the curvature of the drum so that the raising or lowering of the bottom a given dis-

tance increases or diminishes the capacity of the cell by an equal volume. Each nut 14 receives a screw 15 that is suitably swiveled at 16 to the bottom of the cell or compartment.

Erected above the drum is a hopper 17 that is divided into passages or compartments by vertical partitions 17^a coinciding with the vertical transverse partitions in the proportioning drum so that material supplied to the passages of the hopper feeds by gravity into the cells. The movable bottoms 22 of the cells are adjusted by means of a socket wrench 18 fitting the squared end of the screw 15, said wrench having a long handle permitting access to the screw through the hopper. Because the movable bottom is rectangular and just fits in the cell the turning of its supporting screw causes the said bottom to be raised or lowered according to the direction in which the screw is turned or according as the capacity of the cell is to be made greater or less.

The proportioning drum is mounted to 80 rotate under the hopper so that each cell receives its material independently of the others and so that upon a half rotation from the material receiving position each cell discharges its contents into a common chamber 20. The chamber 20 can contain a screw 21 for mixing or partially mixing and discharging the material for further treatment or use. The said screw and hopper can be driven by any suitable power it being convenient to gear the shaft of the screw and the shaft of the proportioning drum together so that the driving of one drives the other.

Within the limits of my claims the parts 85 can be varied without departing from the gist of the invention.

What I claim is—

1. In a machine for proportioning and mixing the components of fertilizer, the combination of a rotary drum having a plurality of distinct cells, means in said cells for varying the capacity thereof, a stationary hopper having distinct passages for feeding different materials to said distinct cells, and a common chamber into which said cells discharge and a mixing device in said common chamber.

2. In a machine for proportioning and mixing the components of fertilizer, the combination of a rotary drum having a plu-

rality of distinct cells, means in said cells for varying the capacity thereof consisting of a plate curved to conform to the curvature of the drum and an axially stationary screw for adjusting said plate, a stationary hopper having distinct passages for feeding different material to said distinct cells, and

a common chamber containing a mixing device into which said cells discharge.

ALGERNON C. EGGERT.
